ADJUSTABLE CYCLE PERCENTAGE TIMER
Charles A. Hunt, Wolcott, and Lewis E. Schoonmaker,
Marion, Conn., assignors to The Sessions Clock Company,
Forestville, Conn., a corporation of Connecticut
Filed Mar. 7, 1963, Ser. No. 263,491
8 Claims. (Cl. 310—69)

The present invention relates to a timing mechanism, and, more particularly, to a new and improved adjustable cycle percentage timer, a device which provides repetitive switching of two-phase cycles at a predetermined frequency. More particularly, the present invention relates to an adjustable cycle timer in which the relative duration of each of the two phases comprising a complete cycle may be readily, manually adjusted, and in which the frequencies of the cycles, themselves, the actual duration of the phases, may be readily, manually adjusted.

The timer of the present invention essentially comprises an adjustable cyclical mechanism movable into either of two conditions or phases for predetermined durations, an electric motor of the type having bi-directional starting and running characteristics for constantly driving the mechanism, and mechanical means in combination with the adjustable cyclical mechanism for periodically reversing the direction of rotation of the motor.

More specifically, the adjustable percentage timer mechanism of the invention includes an electric switch, a cycle plate supporting a pair of stop bars in an adjustably spaced relationship, a special actuating cam having a two-phase camming surface, a motor reversing arm integral with the cam, and an electric motor for driving the actuating cam. In percentage cycling operations, the cam, in accordance with the principles of the invention, is adapted to be driven in a first direction by the motor until the reversing arm strikes the stop bar to stall the motor and allow it to reverse itself to drive the cam in the opposite direction until it strikes the other stop bar and repeats the cycle. The cam is especially shaped so that it maintains the switch in two different conditions during the travel of the reversing arm between the two stop bars. In accordance with the invention, the reversing arm tends to be driven by the motor in a circular path of travel, which travel, however, is limited by the stop bars which, in addition to physically limiting the travel of the cam in a given direction, impart a reversing force to the motor upon impact of the reversing arm therewith. The overall cycle time will be determined by the mutual spacing of the stop bars.

At a predetermined point in the travel of the reversing arm between the stop bars, the especially shaped cam will cause the switch to be transferred from one of its two conditions to the other. The point at which this event occurs is known as the "critical point" and will be determined by the specific shape of the cam. The point on the cam at which the cam moves the switch into one of its conditions is known as the "transfer point," and it will be located in a fixed position on the cam with respect to the reversing arm.

As will be understood, the overall cycle time of the timer may be adjusted by varying the mutual displacement of the stop bars, while the durations of the individual phases may be adjusted relative to one another to achieve relative "percentage times" by varying the displacement of the stop bars relative to the "critical point."

For a more complete understanding of the present invention, reference should be had to the following detailed description taken in conjunction with the accompanying drawings, in which:

FIG. 1 is a side elevational view of a preferred embodiment of the adjustable cycle timer constructed in

2

accordance with the principles of the invention with parts broken away to show details of construction;

FIG. 2 is a cross-sectional view of the mechanism of FIG. 1 taken along line 2—2 thereof;

FIG. 3 is a front elevational view of a modified timer mechanism; and

FIG. 4 is a cross-sectional view of the mechanism of FIG. 3 taken along line 4—4 thereof.

In FIGS. 1 and 2 of the drawing, a flat cycle plate represented by the reference numeral 10 is provided with a pair of semi-circular arcuate slots 11 and 12 separated by a "critical zone" 12a. The cycle plate 10 is held in a spaced relation to a constant speed, electric motor 13, by spacer bars 14 and screws 15. The motor is a self-starting, alternating current, synchronous motor having bi-directional starting and running characteristics. A typical motor of this category is described in greater detail in U.S. Patent No. 3,059,131, granted October 16, 1962 to J. J. Everard, et al. In the illustrated, preferred embodiment, the motor 13 is advantageously a Sessions Clock Company S-4000 motor operating at 115 volts, 60 cycles per second, and is geared down through a suitable gear train 9 to have an output of 20 r.p.m. at the power shaft 16. An electric switch 17, having a pivotable roller lever 18, is mounted to the cycle plate by a pair of nuts and bolts 19. The switch is typically a single-pole, single-throw switch having contacts which are opened and closed by the reciprocating movement of the roller lever 18.

A switch actuating cam 20, having an actuating surface 21 and a reversing arm 22 integral therewith, is fixedly mounted to the output power shaft 16 for rotation therewith by a rivet 16a (FIG. 1) or other suitable means, such as force fitting (FIG. 4). The cam surface 21 is constructed with two contiguous active "on" and "off" portions 21a, 21b which cooperate, respectively, with the roller lever 18 alternately to open and close the switch contacts. The cam surface is said to have a "transfer point" 23, which is the point at which the cam surface 21 opens and closes the switch contacts depending upon its direction of rotation to transfer the switch 19 into its two phases, "on" and "off," for example. As may be clearly seen in FIG. 2, in a preferred embodiment of the invention, the reversing arm 22 is coincident with a radial line extending through the axis of rotation of the cam and the transfer point 23, and is adapted to be rotated by the shaft 16 in a predetermined circular path coincident with the arcuate slots 11, 12.

A pair of cylindrical stop bars 24, 25, having threaded necks 24a, 25a, of reduced diameter, are secured in the arcuate slots 11 and 12, respectively, by wing nuts 26 and washers 27 and may be adjusted to be locked in the slots 11 and 12 at varying distances from one another and from a dead center or "critical" position of the reversing arm 22, the position at which the cam 20 moves the switch into a different one of its two phases. Advantageously, the critical position of the reversing arm and the critical zone 12a are coincident, as are the arcuate slots 11, 12 and the circular path of travel of the reversing arm.

In operation, the electric motor is energized, and, due to its inherent, non-directional, starting characteristics, will start to rotate in either of two directions, clockwise, for example, and continue to rotate until the reversing arm 22 strikes the stop bar 25. The impact of the reversing arm with the stop bar 25 restrains or stalls the motor in the clockwise direction; however, the motor remains free to rotate in the unrestrained counterclockwise direction, opposite to its initial direction of rotation and that of the reversing arm. Due to its inherent, bidirectional characteristics, the motor 13, will, in fact, reverse its direction and, thus, will change the direction of rotation of the cam to counterclockwise. Reversal of the motor 13 tends to be assisted by a small reversing force from the impact of

the reversing arm and the stop bar, which force may be transmitted through the power shaft 16 and the gear train 9. Advantageously, the gear train 9 has a minimum number of gears (e.g., 15:1 ratio from the motor pinion to the output shaft) to minimize losses of forces transmitted therethrough. The reversed motor will then drive the cam 20 in its reversed, counterclockwise direction until the reversing arm strikes the stop bar 24, at which time, the cam is again reversed to re-assume its clockwise direction. During its cyclical travel between the limits imposed by the stop bars 24, 25, the cam will periodically open and close the switch contacts through the roller lever 18 as the cam passes through its "transfer point" 23.

It will be understood that, in accordance with the principles of the invention, the duration for which the switch contacts are made or broken, i.e., "on" or "off," will be dependent entirely upon the displacement of the stop bars from the "critical" or dead center position and the speed of the output shaft 16. Thus, as shown in FIG. 2, the stop bar 25 which controls the duration of the "off" time is much closer to the "critical" or dead center position than the bar 24 which controls the duration of "on" time. Accordingly, each complete cycle of the cam will cause a greater proportion or "percentage" of "on" time than "off" time. The percentage of "on" time to "off" time, of course, may be varied merely by adjusting the displacement of the stop bars relative to the "critical" or dead center position between the slots 11 and 12. The overall cycle time will be determined by the circumferential displacement of the stop bars in the circular path and the speed of the output shaft 16.

Where it is advantageous and desirous to keep the overall cycle time constant, i.e., a fixed mutual spacing of the stop bars 24, 25, but to vary the percentage of "on" and "off" times, the modification shown in FIGS. 3 and 4 may be employed. A separate rotatable circular plate 28 is provided and contains arcuate slots 29, 30, similar in shape and function to the slots 11, 12. Accordingly, a pair of stop bars 34, 35, is secured to the plate 28 by wing nuts 36 to define a fixed cycle time or period. The plate 28 may be rotated relative to the "critical" or dead center position of the reversing arm so that the stop bars fixed to the plate 28 may be displaced relative to the "critical" position without altering their mutual circumferential displacement or the overall cycle time. Advantageously, the rotatable plate 28 is mounted to a support plate 37, similar in function to the plate 10 shown in FIGS. 1 and 2, by a pair of bushings 38, and a clamping button 39 which has a clamping screw 40 to clamp the plate 28 in a selected, adjusted position relative to the "critical" position of the reversing arm 22. Manual rotation of the plate 28 is facilitated by a projecting adjustment tab 41 located on its face. The elements shown in FIGS. 3 and 4, which are identical to those shown in FIGS. 1 and 2, have been given the same reference numerals.

Thus, it will be understood that the repeat cycle timer of the present invention provides an extremely simple and versatile, yet highly efficient and reliable, timer for use in applications requiring adjustable, repetitive, two-phase timing cycle. The novel timer disclosed hereinabove has been found to be well suited for use in conjunction with automatic milking machines wherein the advantageous characteristics of adjustable cycle frequency and adjustable phase durations, adjustable "percentage times," are most important and desirable. Moreover, the timer of the present invention, through the use of a minimal number of parts, affords great economies in manufacture and production without any sacrifice of accuracy, reliability or adjustability.

While the present invention has been described with respect to specific, preferred embodiments by way of illustration only, the scope of the invention is to be limited as set forth hereinafter in the appended claims.

We claim:

1. An adjustable, repetitive, cycle-actuating mechanism, comprising
  - (a) an electric motor having bi-directional starting and running characteristics,
  - (b) a power shaft operatively associated with said motor,
  - (c) output gear means operatively associated with said power shaft,
  - (d) an actuatable mechanism having two conditions,
  - (e) a motor reversing arm rotatable in a predetermined circular path of travel toward, through and beyond a predetermined critical transfer position in said path at which position said actuatable mechanism is transferred to one of its conditions,
  - (f) said reversing arm being fixedly mounted to said power shaft for rotation therewith in said predetermined circular path of travel,
  - (g) an actuating cam fixedly mounted to said power shaft and driven thereby to periodically initiate actuating movement in said actuatable mechanism,
  - (h) said cam having a pair of contiguous active portions cooperating with said actuatable mechanism to maintain said mechanism in one of its two conditions,
  - (i) said cam having a transfer point between said two active positions at which point said cam cooperates with said actuatable mechanism to transfer said mechanism to one of its two conditions,
  - (j) a pair of stop surfaces disposed in said circular path of travel and limiting the rotation of said reversing arm in the direction in which said arm is being driven by said motor, said stop surfaces being mutually, adjustably positionable,
  - (k) each of said stop surfaces being adapted to cooperate with said reversing arm upon impact therewith to stall said motor and to effect a force reversal of said motor,
  - (l) whereby said reversing arm is cyclically oscillated between said stop surfaces in cycles having predetermined frequencies which are a function of the speed of said output shaft and the mutual displacement of said stop surfaces, and,
  - (m) said cam actuates said actuatable mechanism for predetermined durations which are functions of the speed of said output shaft and the displacement of each of said stop surfaces from said critical position.
2. The mechanism of claim 1, which includes
  - (a) plate-like supporting means for said stop surfaces,
  - (b) said plate-like supporting means defining a pair of circular arcuate slots,
  - (c) said slots being substantially coincident with said circular path of travel,
  - (d) said stop surfaces comprising stop bars,
  - (e) said stop bars being adapted to be adjustably supported in said arcuate slots,
  - (f) said slots defining a transfer zone between the ends thereof.
3. The mechanism of claim 2, wherein
  - (a) said transfer zone is substantially coincident with said critical position.
4. The mechanism of claim 2, which includes
  - (a) means for mounting said plate-like means for rotation relative to said critical position.
5. The mechanism of claim 2, wherein
  - (a) said stop bars are substantially cylindrical and have threaded neck portions of reduced diameter,
  - (b) said neck portions are slidably and adjustably mounted in said arcuate slots by wing nut means.
6. An adjustable, repetitive, cycle-actuating mechanism comprising
  - (a) an electric motor having inherent bi-directional starting and running characteristics upon connection to and energization by a voltage source,
  - (b) mechanical means for periodically reversing said

- motor without altering the connection thereof to said source,
- (c) output shaft means operatively associated with said motor and having less than one revolution in any direction between the reversals of said motor, and
- (d) actuating means operatively associated with said shaft to move an actuatable mechanism into at least two conditions between reversals of said motor.
7. A mechanism according to claim 6, in which
- (a) said mechanical means include a reversing arm and 10 a pair of stop surfaces,
- (b) said reversing arm being driven by said motor in a predetermined path,
- (c) said stop surfaces being adjustably disposed in said predetermined path to limit the travel of and to 15 reverse the direction of said motor,
- (d) whereby said motor has a predetermined cycle

5

- time which is a function of the mutual displacement of said stop surfaces.
8. A mechanism according to claim 7, in which
- (a) said reversing arm is maintained in a fixed position with respect to said cam means,
- (b) whereby the relative durations of actuation of the actuatable mechanism are a function of the displacement of said stop surfaces.
